US0D1059936S

(12) United States Design Patent (10) Patent No.: US D1,059,936 S
(45) Date of Patent:  Feb. 4, 2025

(54) CUP

(71) Applicant: StoreBound LLC, New York, NY (US)

(72) Inventors: Evan Marc Dash, New York, NY (US);
Rachel Dash, New York, NY (US);
Yiyang Zhang, Shenzhen (CN); Shelby Scott, New York, NY (US)

(73) Assignee: StoreBound LLC, New York, NY (US)

() Term: 15 Years

(21) Appl. No.: 29/884,713

(22) Filed: Feb. 15, 2023

Related U.S. Application Data

(60) Continuation-in-part of application No. 29/851,468, filed on Aug. 29, 2022, which is a division of application No. 29/723,678, filed on Feb. 10, 2020, now Pat. No. Des. 965,376, which is a continuation-in-part of application No. 29/701,166, filed on Aug. 8, 2019, now Pat. No. Des. 916,542.

(30) Foreign Application Priority Data

Mar. 14, 2019 (CN) 201930103882.8

(51) LOC (15) Cl. 07-02

(52) U.S. Cl.

USPC D7/352
